[57] CLAIM

The ornamental design for a combustion wick for oil stoves, as shown and described.

DESCRIPTION

FIG. 1 is a top perspective view of a combustion wick for oil stoves, showing my new design; and
FIG. 2 is a bottom perspective view thereof, taken on the side opposite that shown in FIG. 1.

The appearance of the sides not fully shown in FIGS. 1 and 2 is apparent from FIGS. 1 and 2.
